UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed July 28, 1922. Serial No. 577,556.

To all whom it may concern:

Be it known that I, CHARLES DAVID BONSALL, a citizen of the United States, and a resident of the city of Pittsburgh, county of Allegheny, and State of Pennsylvania, have invented a certain new and useful Improvement in Car Roofs, of which the following is a specification.

This invention relates principally to car roofs of the all-steel riveted-up type wherein the roofing sheets extend from eaves to eaves of the car and are rigidly secured thereto and have overlapped side marginal portions that are shaped and are rigidly secured to form weather proofing seams or joints that serve as carlines. One of the principal objects of the present invention is to increase the strength and rigidity of the roof by improving the shape and arrangement of the overlapped side marginal portions of the sheets. Other objects are to reduce the weight of the roof, to simplify the construction thereof and to cheapen the cost of manufacture. The invention consists principally in shaping and arranging the cooperating marginal portions of the roof sheets to form hollow weather proofing seams or joints that are better fitted for taking care of contemplated stresses. The invention also consists in the parts and in the arrangements and combinations of parts hereinafter described and claimed.

In the accompanying drawing, wherein like symbols refer to like parts wherever they occur,

Fig. 1 is a plan view of a portion of the car roof embodying my invention;

Fig. 2 is a transverse section through one-half of the roof, the section being taken between seams on the line 2-2 in Fig. 1;

Fig. 3 is a vertical cross-section through one of the seams or joints at the ridge on the line 3-3 in Fig. 1;

Fig. 4 is a similar section adjacent to the side plate on the line 4-4 in Fig. 1;

Figs. 5 and 6 are vertical cross-sections embodying a modified form of seam or joint construction, the sections being taken at points corresponding to the lines of section 3-3 and 4-4, respectively, in Fig. 1; and

Figs. 7 and 8 are like views illustrating still another modified form of seam or joint construction.

The roof shown in Figs. 1 to 4, inclusive, of the accompanying drawing comprises

metallic roof sheets 10 that extend transversely of the car from eaves to eaves thereof with their side margins overlapped. The roof sheets slope upwardly from the eaves towards the ridge and are supported at their eaves ends on metal side plates 11. The roof sheets are rigidly secured to the side plates 11 by rivets 12 and are provided with down-turned eaves flanges 13 which overhang the outer edges of the side plates.

One side margin of each sheet is pressed up to form a hollow strengthening rib A, and the other side margin is pressed up to form a hollow strengthening rib B, both ribs extending from end to end of the sheet. The roof sheets are assembled on the car by placing the type A rib of one sheet over the type B rib of the next adjacent sheet, whereby the lapped ribs A and B by a row of rivets 14. Thus, the overlapped portions of adjacent roof sheets are rigidly secured together from side plate to side plate by two rows of rivets, the row of rivets on one side of a seam or joint extending through the overlapping side marginal flange 15 of one sheet and the underlying body portion of the other sheet, and the row of rivets on the opposite side of said seam or joint extending through the overlapping body portion of said first mentioned sheet and the underlying side marginal flange 16 of said second mentioned sheet.

The ribs of both types are preferably of inverted channel-shaped section and have a maximum depth at the ridge and gradually decrease in depth towards the eaves where they are curved downwardly and merge into the plane of the sheets at the eaves ends thereof. The type A ribs have a minimum width at the ridge, at which point they closely embrace the type B ribs, and widen gradually to the eaves; and the type B ribs have a maximum width at the ridge and gradually decrease in width to the eaves. This widening or tapering of the cooperating ribs of the types A and B in opposite directions on each side of the ridge produces a seam construction comprising a pair of overlapped channels whose side walls are in contact at the ridge and diverge from each

other on opposite sides thereof to form a seam or joint whose cross-sectional shape gradually changes from an inverted channel of double thickness at the ridge to a double box-girder at the eaves.

The sheets are preferably pressed from blank sheets of uniform width, whereby the gradual decrease in depth of the ribs A from the ridge towards the eaves affords a surplus of metal which is utilized in securing a uniform widening of said ribs from the ridge to the eaves; and the gradually decreased depth and width of the ribs B from the ridge towards the eaves affords a surplus of metal which is utilized in gradually increasing the width of the adjacent side marginal flange 16 of the sheet from the ridge towards the eaves. The side marginal flange 15 that is located outside of the type flange 16 of each sheet is of substantially uniform width except for its eaves end portions, which portions, together with the corresponding eaves end portions of the side marginal flange 16 located adjacent to the type B rib, widen gradually to the eaves by reason of the surplus of metal afforded by the down-turned eaves end portions of said ribs.

Running boards 17 extend longitudinally of the car at the ridge and are bolted or otherwise rigidly secured to the upwardly offset flanges of running boards saddles 18, which rest on and are riveted to the tops of seams or joints.

It is noted that the seam or joint produced by the cooperating ribs of the types A and B accomplish the various functions of the carline. The cross-sectional shape of the seams or joints at the ridge serves to increase the vertical carrying capacity of the roof, and the cross-sectional shape of the seams at the eaves serves to take care of the stresses that tend to rack and twist the car body and distort it endwise. This increased strength in the seams or joints enables a roof to be produced that will be stiffer and stronger than previous roofs of the same weight of metal.

In the modified seams or joints construction shown in Figs. 5 and 6, the overlapping marginal portion of one sheet is provided with an upstanding hollow rib A¹ of gradually decreasing depth and gradually increasing width from the ridge to the eaves; and the underlying marginal portion of the next adjacent sheet is formed with an upstanding rib or flange B¹ of inverted L-shaped section. The tops of the lapped ribs A¹ and B¹ are riveted together; and the overlapping marginal flange of one sheet is riveted to the underlying body portion of the other sheet. The outer side wall of the rib A¹ of one sheet is in contact at the ridge with the upstanding web of the L-shaped flange B¹ of the other sheet and diverges

therefrom on opposite sides of the ridge, thus forming within the hollow seam a hollow box-girder that gradually increases in width from the ridge to the eaves.

In the modified seam or joint construction shown in Figs. 7 and 8, the overlapping side marginal portion of one sheet is provided with a hollow rib A² of gradually decreasing depth and width from ridge to eaves. The underlying marginal portion of the other sheet is provided with a rib or seam flange B² of substantially uniform width whose cross-sectional shape changes from an inverted L-shaped section at the ridge to an inverted channel at the eaves; and the lateral flange that appears in the eaves section (Fig. 8) is the surplus of metal resulting from the downwardly curved eaves end portions of said rib. The tops of the cooperating ribs A² and B² are riveted together; and the overlapping marginal flange of one sheet is riveted to the underlying body portion of the other sheet. This arrangement produces a hollow seam having a box-girder formed therein that gradually increases in width and depth from the eaves to the ridge.

Other modifications of the form and arrangement of the parts may be made in view of the foregoing description of the invention, and I do not wish to be restricted to the exact forms and arrangements shown in the drawing.

What I claim is:

1. A car roof comprising a plurality of metal roof sheets connected along their side margins by raised seams, the seam portion of the upper sheet being of inverted channel shape, and the lower sheet having an L-shaped flange at its side margin under and secured to the upper sheet, and the marginal portion of the upper sheet being secured to the body of the lower sheet, the vertical portion of said L-shaped flange being spaced horizontally from the vertical portions of the overlapping sheet.

2. A car roof comprising a plurality of metal sheets connected along their side margins by raised seams, the seam portion of the upper sheet being of inverted channel shape and the lower sheet having an L-shaped marginal portion which is covered by the seam portion of said upper sheet, the top of said L-shaped portion being rigidly secured to the top of said inverted channel, and the outer margin of the upper sheet being secured to the body of the lower sheet, the vertical part of said L-shaped portion diverging horizontally from the outer wall of said channel member.

3. A car roof comprising a plurality of metal roof sheets extending from eaves to eaves and having hollow ribs formed in their marginal portions and arranged to overlap each other and be secured together to form hollow seams, the side walls of the

overlapping ribs diverging from each other between ridge and eaves to form hollow box-girders within said seams.

4. A car roof comprising a plurality of metal roof sheets extending from eaves to eaves and having hollow ribs formed in their marginal portions and arranged to overlap each other and secured together to form hollow seams, one of the overlapping ribs of each of said seams being of varying width between the ridge and the eaves, and diverging horizontally from the other rib of said seam thereby forming hollow box-girders within said seams.
5. A car roof comprising a plurality of metal roof sheets extending from eaves to eaves and having hollow ribs formed in their adjacent side marginal portions that are lapped and rigidly secured together to form hollow seams, the side walls of the ribs of a seam diverging from each other on opposite sides of the ridge to form hollow box-girder portions within said seams.
6. A car roof comprising a plurality of metal roof sheets extending from eaves to eaves and having hollow ribs formed in their side marginal portions that are lapped and secured together to form hollow seams, one rib of a seam being of varying width from ridge to eaves, and diverging horizontally from the other rib of said seam whereby said seam has a hollow box-girder portion formed therein whose width varies from ridge to eaves.
7. A car roof comprising a plurality of metal roof sheets extending from eaves to eaves and having hollow ribs formed in

their side marginal portions that are lapped and secured together to form hollow seams, the overlapping rib of a seam being wider at the eaves than at the ridge, and diverging horizontally from the lower rib of said seam whereby said seam has a hollow box-girder portion formed therein of greater width at the eaves than at the ridge.

8. A car roof comprising a plurality of metal roof sheets extending from eaves to eaves and having hollow ribs formed in their side marginal portions that are lapped and secured together to form hollow seams, the overlapping rib of a seam being wider at the eaves than at the ridge, and the underlying rib being of greater width at the ridge than at the eaves.

9. As an article of manufacture, a car roof sheet having a portion adjacent to each side margin formed into a hollow strengthening rib, the rib at one side margin being wider at each end of the sheet than at the middle thereof and the rib at the other side margin of the sheet being wider at the middle of the sheet than at each end thereof.

10. As an article of manufacture, a car roof sheet having a portion adjacent to each side margin formed into a hollow strengthening rib, the rib at one side margin increasing in width from the middle of the sheet towards each end thereof and the rib at the other side margin increasing in width from each end of the sheet towards the middle thereof.

Signed at New Kensington, Pa., this 22 day of July, 1922.

CHARLES DAVID BONSALL
